SELF-PROPELLED COMBINE

Shelly A. Bulin, Davenport, Iowa, assignor to J. I. Case
Company, Racine, Wis., a corporation of Wisconsin

Filed Sept. 13, 1966, Ser. No. 4,589

Term of patent 7 years

(Cl. D40—1)

FIG. 3

FIGURE 1 is a perspective view taken from the top and left side of a self-propelled combine embodying my new design;

FIGURE 2 is a perspective view taken from the bottom and right side of the combine shown in FIG. 1;

FIGURE 3 is a left side elevational view of the combine shown in FIGS. 1 and 2; and

FIGURE 4 is a top plan view of the combine shown in FIGS. 1, 2 and 3.

The dominant features of the design reside in the portions shown in full lines.

The broken lines illustrating the header mechanism has been omitted in FIGS. 1, 2 and 4 for convenience of illustration.

This is a continuation-in-part of design application Ser. No. D. 86,361, filed July 29, 1965 and now abandoned.

I claim:

The ornamental design for a self-propelled combine, substantially as shown and described.
